UNITED STATES PATENT OFFICE.

HENRY J. PLANT, OF ROCHESTER, NEW YORK, ASSIGNOR TO DEFIANCE CHECK WRITER CORPORATION, OF ROCHESTER, NEW YORK, A CORPORATION.

PRINTING-MACHINE.

1,281,652.

Specification of Letters Patent.

Patented Oct. 15, 1918.

Application filed July 10, 1917. Serial No. 179,636.

To all whom it may concern:

Be it known that I, HENRY J. PLANT, a citizen of the United States, and resident of Rochester, in the county of Monroe and State 5 of New York, have invented certain new and useful Improvements in Printing-Machines, of which the following is a specification.

The present invention relates to printing machines, and more particularly to the type 10 in which the work is fed in the direction of the printing line by a movement in the printing member to carry the work along with said member, an object of this invention being to provide a construction, in which the 15 printing member moves relatively to a platen, while coöperating with the latter so as to shift the work on the platen without any movement in such platen. Another object of the invention is to provide in a construction operating 20 as mentioned, coöperating faces on the platen and the printing member so formed that the work is held to the printing member while permitted to move freely on the platen. Another object of the invention is to provide 25 in a printing machine in which the printing element moves in the direction of the printing line, a simple form of mechanism for moving the platen toward the printing member and holding it in such position until the 30 end of the feeding movement of the printing member is completed.

To these and other ends the invention consists of certain parts and combinations of parts all of which will be hereinafter 35 described, the novel features being pointed out in the appended claims.

In the drawings:—

Figure 1 is a horizontal section through a printing machine embodying the present invention;

Fig. 2 is a vertical section through such machine;

Fig. 3 is a section on the line 3—3, Fig. 2;

Fig. 4 is a section on the line 4—4, Fig. 3;

Fig. 5 is a fragmentary section showing the platen in coöperation with the printing wheel;

Figs. 6 and 7 are, respectively, a plan and a sectional view of the platen; and

Fig. 8 is a detail view, showing the type of one of the printing lines enlarged.

The invention is, in this instance, embodied in what is known as a check writer, or a machine for writing words into checks, or other negotiable instruments, to represent 55 an amount for which said instrument will be payable. In the illustrated embodiment there is employed a printing element or member 1, in the form of a type wheel, having on its periphery a plurality of parallel 60 lines 2 of type, each line printing a word which maybe combined with words printed by the other line, to write into a check any reasonable amount. In this instance, the type lines extend parallel with the axis of 65 the printing wheel 1, and the latter is mounted on a noncircular shaft 3, so as to move in the direction of the axis of the shaft, but to turn with such shaft. The shaft is preferably journaled in the opposite side walls of 70 the overhanging portion 4 of the casing, the overhanging portion projecting over a work-supporting plate 5 on the base 6 of the casing, from the rear edge of said work-supporting plate. A bottom plate 7 is provided 75 on the overhanging portion and this bottom plate has an opening 8, over which any one of the lines of type 2 on the printing member 1 may be presented by turning the shaft 3 to move the lines transversely of their 80 lengths. The turning of the shaft may be effected by a hand wheel 9 arranged on the shaft on the exterior of the overhanging portion, said hand wheel having a dial wheel 10 integral therewith for coöperation with a 85 fixed dial or indicator arranged on the casing. The characters on the dial 10 corresponding with the words on the printing wheel, so that when any character on the dial is brought opposite the indicator a word corresponding to said character is positioned 90 above the opening 8.

For coöperating with the printing element or member 1 an ink roller 11 is provided. This roller may have flanges 12 at 95 opposite edges coöperating with the said face of the wheel 1, so that the roller will move with the printing wheel 1 on an elongated shaft 13 extending parallel with the shaft 3. The shaft 13 may be supported by 100 a swinging arm 14, on which a spring 15 acts to press the roller toward the printing wheel.

The printing is effected by moving the work, which has been supported upon a table 5, upwardly through the opening 8 into engagement with the type line disposed above said opening. This movement of the work is produced by a platen 16, which operates through a slot in the table 5 mounted for vertical movement within the base 6. In this instance, the platen is embedded in a block 17 movable at its ends in guides 18 on opposite sides of the base 6, the block 17 having depending portions 19 at opposite ends provided with inwardly-extending pins or projections 20, which lie in close proximity to horizontal guides 21. On these guides 21 a slide plate 22 is movable, said slide plate having notches 23 at opposite sides which receive the pins or projections 20 when the platen is in its lowermost position. When the slide plate moves in one direction, an inclined wall 24 of each notch or recess 23 acts as a cam which passes beneath the adjacent projection 20 and elevates the latter so as to move the platen 16 upwardly into contact with the type line 2 above the opening 8. The platen is so held until the projections 20 reach one edge of the slide 22 when the platen will be depressed by the action of the spring arms 25. On the return movement of the slide 22, cam faces 26, at one edge of the slide, will engage the projections 20 and shift the plate 22 away from its guides 21, thus permitting the plate to return to the position shown in Fig. 2, without affecting the position of the platen 16. In order that the cam plate 22 may partake of the sliding and lateral movement, it is preferred to mount the latter at one end of a rod 27, which is guided at 28 in the rear wall of the casing to partake of a longitudinal and slight rocking movement. A coil spring 29, anchored at one end at 30 to the base 6, and at the other end at 31 to the slide, tends to hold the slide plate 22 toward the guides 20, and also to shift said slide 22 in one direction on the guides. The movement of the slide in the other direction is preferably effected by a crank arm 32 arranged on the exterior of the casing on a rock shaft 33, which, by a slotted arm 34, connects with a pin 35 on the rod 27.

Movement of the printing member in the direction of the printing line may be effected in any suitable manner. In this instance, a slide 36 is movable on the guides 37, which are parallel with the axis of rotation of the printing member, the movement of the slide being produced in this embodiment by a slotted arm 38 mounted upon a vertical rock shaft 40 and engaging a pin 41 on the slide. The lower end of the rock shaft has a slotted arm 42, which receives a pin 43 on the rod 27, so that when the rod 27 is moved rearwardly by the crank handle 32, the shaft 40 will be rocked and transmit motion to the

slide 36 which, in turn, transmits movement to the printing member.

Connection between the slide 36 and the printing member is so constructed that the printing member, notwithstanding a constant or uniform movement in the slide 36, will be moved variable distances corresponding to the lengths of the words on such printing member. This is effected by providing the printing member with a plurality of grooves or notches 44 in its periphery, the ends 45 of these notches serving as stops which are located at different distances from the common plane formed by one side of the printing wheel. The slide 36 has a projection 46 and a projection 47, the projection 47 coöperating with one face of the printing wheel, while the projection 46 is adapted to enter the grooves 44 in order to coöperate with the shoulders or stops 45 formed by the ends of said grooves. It is apparent that, when the slide 36 is moved in a direction to feed the work, the projection 46 will move in one of the grooves 44 without producing any movement in the printing wheel until the end of the groove is reached, after which the projection will coöperate with such end and shift the printing wheel a distance corresponding to the work printed. Upon the return movement of the slide 36, the projection 47 will coöperate with the printing wheel and return the latter to its initial position. To the end that the printing wheel will not shift with the slide, until the projection 46 is engaged with an end wall 45 of the slot, a spring arm 48 is mounted on a slide and acts on the printing wheel in a direction to hold the latter in its initial position, until a stop 45 has been engaged by the projection 46.

In the operation of the invention, the work is placed face upward upon the work support 5, and beneath the opening in the overhanging portion in the casing. The printing wheel is turned by means of the thumb wheel 9 to present the desired word at the printing point, the indicator 10 being employed for locating this word on the type wheel. The crank handle 32 is now moved forwardly, thus drawing the rod 27 to the rear and causing the platen 16 to be elevated due to the engagement of the projections 20 with the slide 22. After the work has been pressed against the printing wheel to produce the printing, the projection 46 on the slide 36 engages a stop 45 formed by the inner end of one of the slots 44. This causes the type wheel 1 to move with the slide 36 a distance corresponding substantially to the length of the word which has been printed. During this movement of the type wheel, the platen remains stationary, and the work is drawn over the same, due to the fact that the faces of the type are provided with their points which penetrate the paper within the

grooved upper face of the platen. Owing to the fact that the type faces penetrate the paper, the ink supplied to the type wheel by the roller 11 is caused to be absorbed by the paper, and this renders the erasure of the printed matter impossible. About the time that the printing wheel 1 has reached the limit of its feeding movement, the platen 16 lowers, due to the fact that the projections 20 pass beyond the end of the slide 22. With the release of the handle 32 the printing wheel 1 returns to its normal position, and the slide 22 moves forwardly over the projections 20 until such time that said projections shall enter again the notches 23, so that the parts will assume the positions shown in Fig. 2, the return of the parts being effected by the spring 29.

A printing machine constructed in accordance with this invention makes it possible to feed work variable distances without the provision of complicated feeding devices. It will be noted that the platen and the printing element or member have three relative movements, one transversely to the printing line to present any desired type line to printing position, another in which the platen moves toward the printing wheel to produce the printing action, and still another, in which the printing wheel moves in the direction of the printing line over the platen for feeding the work.

I believe myself to be the first to feed work in a printing machine by the movement of a printing member in the direction of the printing line over a platen which will simultaneously engage the work throughout the length of the printing line, the length of the platen being such that it will maintain its engagement with the printing element or member during the movement of the said element or member over the platen.

What I claim as my invention and desire to secure by Letters Patent is:—

1. A printing machine embodying a printing element having a printing type line, and a platen, the platen having a surface for co-operating simultaneously with the entire printing type line of the printing element, the printing element and the platen being relatively movable to produce the printing action and the printing element being movable relatively to the platen in the direction of the printing line to produce the feeding of the work.

2. A printing machine embodying a printing element having a plurality of parallel printing type lines, a common platen arranged to co-operate simultaneously with any one of said lines throughout the length of said line, the platen and the printing element having three relative movements, one relative movement transversely of the printing lines to cause the platen to co-operate with any line; another relative movement

in which one part moves toward the other part to effect the printing; and still another relative movement in which the printing element moves in the direction of the printing line while co-operating with the platen in order to feed the work over the platen.

3. A printing machine embodying a printing element mounted to turn about a suitable axis and having a plurality of lines of type of different lengths extending parallel with said axis, a common platen arranged to co-operate simultaneously with the entire length of a line of type, the printing element while pressing the work against the platen being movable relatively to the platen in the direction of the turning axis to shift the work on the platen.

4. A printing machine embodying a printing element having a printing surface and a platen co-operating therewith, the co-operating face of the platen in the direction of the printing line being of greater length than that of the printing element in the direction of the printing line, and the printing element being movable relatively to the platen in the direction of the printing line while such faces are co-operating in order to move the work over the platen.

5. A structure as set forth in claim 4, in which the platen is provided with parallel grooves lying parallel with the direction of the printing line.

6. A structure as set forth in claim 4, in which the platen is provided with parallel grooves lying parallel with the direction of the printing line and the printing element has its co-operating surface formed with points which enter into the grooves of the platen to perforate the work so that the latter will be held to the printing element while the said element is moved over the platen to feed the work.

7. A printing machine embodying a printing member having a plurality of parallel lines of type thereon and two movements one transversely of said lines of type to present any one of the lines to printing point and the other to shift the lines of type in the direction of the printing line to feed the work, a platen, and mechanism for moving the platen toward the printing member including a slide adapted when moved in one direction to shift the platen toward the printing member, to hold such platen in engagement with the printing member while the latter is shifting its type line in the direction of the printing line, and to permit such platen to move away from the printing member as the feeding of the work is completed.

8. A printing machine comprising a printing wheel movable in the direction of its axis to feed the work and provided with a plurality of stops situated at different dis-

tances from one side of the wheel, and mechanism for shifting the wheel in the direction of its axis embodying an operating member having a portion for coöoperating with the 5 stops to shift the wheel in one direction and a portion for coöoperating with the opposite side of the wheel to shift the latter in the other direction.

9. A structure as set forth in claim 8, in which a spring is mounted on the operating 10 member to coöperate with the printing wheel to hold the latter against movement until the portion of the operating member engages the stop.

HENRY J. PLANT.
